CLAIM

The ornamental design for a mathematical colored-numbered puzzle one board game as shown and described.

DESCRIPTION

FIG. 1 is a front perspective view of a mathematical colored-numbered puzzle one board game according to my new design;

FIG. 2 is a front perspective view with glass cover pulled half way down of the mathematical colored-numbered puzzle one board game of FIG. 1;

FIG. 3 is a top view of the mathematical colored-numbered puzzle one board game of FIG. 1;

FIG. 4 is a bottom view of the mathematical colored-numbered puzzle one board game of FIG. 1;

FIG. 5 is a left side view of the mathematical colored-numbered puzzle one board game of FIG. 1;

FIG. 6 is a right side view of the mathematical colored-numbered puzzle one board game of FIG. 1; and,

FIG. 7 is a rear perspective view of the mathematical colored-numbered puzzle one board game of FIG. 1.

All surface ornamentation is flat and has no depth characteristic. The board resides directly underneath the glass cover.

1 Claim, 5 Drawing Sheets
